UNITED STATES PATENT OFFICE.

JOHN TORRENT, OF MUSKEGON, MICHIGAN.

SAWMILL-CARRIAGE.

No. 839,338.

Specification of Letters Patent.

Patented Dec. 25, 1906.

Application filed July 25, 1905. Serial No. 271,200.

To all whom it may concern:

Be it known that I, JOHN TORRENT, a citizen of the United States, residing at Muskegon, in the county of Muskegon and State of Michigan, have invented a new and useful Sawmill-Carriage, of which the following is a specification.

This invention relates to sawmill-carriages, and in particular to fluid-pressure-actuated mechanism for driving or feeding the carriage through the medium of a piston and a piston-rod.

The object of the present invention is to cushion the piston at each limit of its stroke, and thereby absorb the jars which are incident to the stopping and changing of direction of movement of the piston.

While the present cushioning means is partially active at the limit of each stroke of the piston, it is particularly designed as an emergency device and does not come into full operation until the piston passes its usual limit by reason of breakage of the piston-rod or by reason of the engine getting beyond the control of the operator. It is therefore the main purpose of the cushioning means to prevent the piston from striking the outer end of the cylinder should said piston travel beyond its normal limit, thereby to prevent damage to the end of the cylinder and to other parts of the apparatus.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a perspective view of a sawmill-carriage and fluid-pressure-feed mechanism equipped with the cushioning means of the present invention. Fig. 2 is a longitudinal sectional view of the carriage at its forward limit. Fig. 3 is an enlarged fragmentary sectional view illustrating the cushioning-springs located in opposite ends of the cylinder.

Like characters of reference designate corresponding parts in each and every figure of the drawings.

For the purpose of illustrating the application and operation of the present invention a

sawmill carriage 1 of any common or approved form has been shown in the accompanying drawings, said carriage being mounted to work back and forth upon guideways 2, so as to approach and recede from the circular saw 3.

The means for working the carriage back and forth consists of a cylinder 4, supported independently of the carriage and beneath the same in rear of the saw. Within this cylinder there is a piston 5, having a piston-rod 6 working through a suitable stuffing-box 7 in the rear end of the cylinder, the outer extremity of the rod being connected to the rear end of the carriage in any suitable manner—for instance, by means of an appropriate hanger. (Shown at 8 in Figs. 1 and 2 of the drawings.) Steam or other fluid-pressure is admitted to the ends of the cylinder through the medium of a four-way controlling-valve 9, included in the service-pipe, which has one branch 10 leading to the left-hand end of the cylinder and another branch 11 leading to the right-hand end of the cylinder. The four-way valve 9 is under the control of the sawyer by means of any suitable mechanism, including a connecting-rod 12.

In practice steam being admitted to one end of the cylinder the piston will be driven to the opposite end thereof, and through the medium of the piston-rod 6 and hanger 8 the carriage will be moved with the piston. When the piston has completed its movement in one direction, the controlling-valve is actuated to admit steam to the other end of the cylinder, and thereby drive the piston back to its original position, and thus move the carriage back to its original position. During the back-and-forth movement of the carriage the latter acquires considerable momentum, which added to the sudden stopping of the piston at each limit of its movement produces jars which are exceedingly injurious to the carriage and other parts of the sawmill. To obviate this jarring of the sawmill-carriage and other parts of the mill, a helical spring 13 is provided within each end of the cylinder, so as to receive the impact of the piston, and thereby cushion the latter and absorb the usual jars incident to the sudden stopping and change of direction of movement of the piston. By the employment of the springs or cushioning devices the piston, and consequently the sawmill-carriage, are not suddenly stopped, but gradually stopped by the resistance of one or the

other of the springs, and therefore none of the mechanism of the mill is subjected to violent jars, which insures an easy and regular operation of the carriage.

5 It will here be explained that while the inner end of each spring is in the path of the piston the latter normally stops before the full resistance of the spring is encountered; but should the piston travel beyond its normal 10 limit through any cause the full cushioning effect of the spring will be exerted upon the piston to prevent contact of the latter with the end of the cylinder, whereby breakage of the end of the cylinder is prevented and all 15 jar is absorbed by the spring, which prevents damage to the other portions of the mill.

From the foregoing description it will be understood that the application of the present invention requires no change or alteration 20 whatsoever in the sawmill-carriage nor in the steam-actuated feed mechanism therefore, nor does the application of the invention interfere with or change the operation of the mill, but, on the other hand, renders the operation thereof smooth and regular.

Having thus described the invention, what is claimed is—

25 1. A fluid-pressure cylinder having com-

bined inlet and exhaust ports located inwardly from its ends to provide terminal 30 spaces for entrapment of fluid-pressure to cushion the piston, and emergency cushioning devices within the cylinder comprising helical springs each permanently abutting a head of the cylinder and disposed to become 35 active when the piston exceeds the limit of its movement at either end of its stroke.

2. The combination of a reciprocatory carriage, a fluid-pressure cylinder mounted independently of the carriage and provided 40 with combined inlet and exhaust ports disposed inwardly from its ends to provide terminal spaces for entrapment of fluid-pressure, a piston working in the cylinder, a piston-rod connected to the carriage, and helical 45 springs within each end of the cylinder and disposed for engagement by the piston when it exceeds its limit of movement at either end of its stroke.

In testimony that I claim the foregoing as 50 my own I have hereto affixed my signature in the presence of two witnesses.

JOHN TORRENT.
